PARKING METER

Edwin H. Allen, Jr., Cameron, Mo., and Adolph E. Yoss, Benton, Ill., assignors to J. W. Menhall, Benton, Ill.

Application October 5, 1950, Serial No. 188,564

14 Claims. (Cl. 194—78)

This invention relates to time operated coin controlled mechanisms and in particular to those mechanisms known as parking meters.

In general, there are two broad types of parking meters; one being the so called automatic type wherein the coin releases a prewound mechanism, and the other being the so called manually controlled type wherein the insertion of a coin permits the operation of a mechanism to be wound and to effect the setting and timing operation. The present invention is of the latter type wherein the coin is availed of to permit the mechanism to be wound, and through various instrumentalities, control the parking period.

A parking meter mechanism of the class in which this invention is found, has been previously shown and described in the United States Patent No. 2,228,396, to Martin, and the present invention relates to improvements in parking meters of the type generally shown in said Martin patent.

It is an object of this invention to provide a universal type of parking meter which may be controlled by a plurality of different coins to permit a setting of the parking meter for a plurality of different times.

One object of this invention is to provide a mechanism wherein the parts may be largely metal stampings with the parts so related as to perform their necessary operations in the most efficient manner. A still further object is to include in the mechanism, positive action means for setting the coin controlled apparatus into operation for a predetermined period of time by availing of the coin to perform a definite part of the sequence of operation of the setting instrumentalities, and to permit the use of different coins, or a plurality of coins of the same denomination, in a manner similar to that set forth in the United States Patent No. 2,228,396, hereinbefore referred to.

A still further object of this invention is to provide a mechanism including parts which may be operated to effect cumulative timing action which may be desirable where coins of different denominations or a plurality of coins are availed of, to set the time operated coin controlled mechanism into operation. A still further object is to enable substantially the same parts to be used and by substituting one part, eliminate the cumulative feature, in those jurisdictions wherein such a feature is not thought to be desirable.

A still further object is to form the parts of metal stampings as hereinbefore set forth, whereby the said metal stampings may be made of stainless steel or other noncorrosive material, to reduce or minimize the possibility of corrosion which is present in parking meters in general, due to the fact that they are subjected to all types of weather conditions. The corrosion is known to have a deleterious effect on the operation of parking meters of the types in use today and, therefore, the above referred to contemplated use of a noncorrosive metal is of definite advantage.

A still further object of this invention is to incorpo-

2

rate novel features which will enable the proper operation of the mechanism even though certain portions thereof may become initially inoperative due to condensation of moisture and subsequent temporary freezing of the parts together. The foregoing is eliminated in the parking meter of this invention by the provision of means whereby initial operation of the meter with the coin in place effects an abutment of various parts to perform the releasing operation above mentioned by impact means.

A still further object of this invention is to so arrange the parts whereby effective means are provided to prevent the possibility of overloading of the spring or clock mechanism incorporated therein.

15 A still further object of the invention is to provide means to effectively control the period of time for which the mechanism may be set in accordance with the size of the coin and to prevent manipulation of the coin in a manner whereby any additional period of time might result.

20 A still further object of this invention is to provide means to prevent operation of the mechanism whereby an additional period of time might be obtained by pumping the apparatus, the said pumping being heretofore availed of in certain instances in parking meters which have not incorporated the improvements of this invention to prevent such action from taking place.

25 Other novel features of the invention and further objects will be set forth in the specification and claims appended hereto and in the drawings which disclose the features of this invention wherein:

30 Figure 1 is a front elevation of the parking meter of the invention, partly sectioned, showing the general arrangement of certain of the parts.

35 Figure 2 is a front elevation, partly in section, with certain of the parts of Figure 1 omitted therefrom to show more clearly the relationship of various parts of the parking meter.

40 Figure 3 is a front elevation similar to Figure 2 but with certain of the parts of Figure 1 shown thereon and in different position.

45 Figure 4 is a side elevation, partly in section, with certain portions broken away to show the location of the clock mechanism and the relationship of the coin controlled parts.

50 Figure 5 is a view showing a detail of an important assembly in the invention.

Referring to the drawings, the meter of this invention is shown as being comprised of a base member 1 adapted to be supported on a post or the like in a manner well known in the art, the said base member being engaged with a casing 2 of substantially rectangular conformation and being formed so as to enclose therein mechanism to be hereinafter described. Adjacent the upper portion of the casing 2 and over an opening 3 therein a substantially hemispherical transparent dome member 4 is shown fastened in any suitable way adjacent the opening 3. A guard member 5 is provided to surround and protect the dome 4 and is secured to the upper portion of the casing 2 in any well-known manner. Referring now to Figure 2, wherein the casing 2 has been removed to permit more clearly illustrating the parts now to be described, a meter assembly body member 6 is suitably fastened to the base member 1, as by means of the cap screws 7, so as to be supported thereabove. Said body member 6 is provided with an outwardly extending portion 8 having an opening adapted to be engaged by a screw 9 of a handle 10. The handle 10 is fitted with a coin follower 11, the said coin follower being fixed against relative movement within the handle 10, which is hollow, by means of the engagement of a hole in the follower 11 by the screw 9 and a suit-

able rivet 12 fixed in the said handle. It will be seen from the foregoing that the handle may be moved in the direction of the arrows of Figure 2 about the screw 9 as a pivot and will carry with it the coin follower 11 for operation in a manner to be hereinafter set forth. It should be noted that the coin follower 11 is provided with a shoulder portion 13 for abutment with a ratchet dog 14, the said ratchet dog being pivoted at 15 to the body member 6 previously referred to. The said coin follower 11 is further provided with a cam surface 16 adapted to coact with a coin during the operation of the mechanism, as will be further described during its operating movement. The body member 6 is formed with a recess or slide receiving opening 17, the said opening 17 being adapted to receive therein a reciprocating slide 18. The slide 18 includes a rectangular section and is formed with a laterally extending portion having the cam surfaces 19 and 20 thereon. In addition, the laterally extending portion of the slide 18 is provided adjacent its upper surface with notches 21 for coaction with the ratchet dog 14 hereinbefore referred to in a manner to be described. The said ratchet dog 14 is held in engagement with the notches 21 by means of a suitable spring member 22, the said spring member being supported on the body 6 at the point 23 near the middle of the said spring member and at one end in engagement with a rib 24 formed in the body member 6 and forming a part of the opening or recess 17. It will be noted that the ratchet dog 14 is so arranged as to permit movement of the slide 18 rightwardly, as seen in Figure 2, but to normally prevent movement of the said slide in a leftward manner. As will be hereinafter described, said ratchet dog 14 is provided with an ear 25 adapted to coact with the portion 13 of the handle 10 when the said handle 10 has been moved from the position shown in Figure 2 into a substantially vertical position about the pivot point 9, whereby the said ratchet dog is raised out of engagement with a notch 21, thus permitting the slide 18 to move in a leftward direction, as seen in Figure 2, for the purposes to be hereinafter explained.

An auxiliary ball lifter arm 26, shown in Figure 2, being formed of a round wire or the like, is pivoted at 27 to the body member 6 and is formed adjacent its other end with a transversely extending portion 28 adapted to abut a ball lifter actuator 29 pivoted about an arbor 30. The actuator 29 is formed of flat stock having an enlarged bearing portion 31 supported on the arbor 30, previously referred to, for movement thereabout, and is provided adjacent its free end with a transversely extending portion 32. The body member 6 is provided with a post 33 at one corner thereof, adapted to receive and support a ball lifter 34 of wire or the like, the said member 34 being formed so as to include a ball abutting section 35 at one end and a lever section 36 at the other end adapted to coact with the transversely extending portion 32 of the actuator 29 hereinbefore referred to.

The body member 6 is fitted with a post 37 supporting thereon a ball-like indicator 38, the said ball member 38 being adapted to slide upwardly and downwardly on the post 37 for indicating purposes to be hereinafter related.

It will be noted that the slide member 18 is formed adjacent one end, with a cam portion 39, said cam portion being adapted to coact with a suitably formed camming section 40 of the auxiliary ball lifter 26 in a manner to be set forth.

The slide member 18 above referred to is additionally provided with a coin release arm 41 suitably fixed thereto as by means of the rivet 42. A post 43 is likewise fixed to the slide member 18 for purposes to be hereinafter set forth. A coin slot is provided in the face of the body member 6 by the rib 44 and a corresponding surface 45 formed in the said body member 6. A suitable transparent window 47 is secured over the coin slot by means of the screws 48, whereby a coin may be visible therethrough when in the position shown in Figure 1, being

supported in that position by means of an inwardly extending shoulder 49 formed on the coin release arm 41 previously mentioned, when the said coin release arm is in the position of Figure 1. Referring again to Figure 2, a slide cover plate 50 of substantially rectangular outline is provided, having a rectangular recess 51 therein to permit the post 43 and the coin release arm 41 to reciprocate when carried back and forth by the slide 18. The said slide cover plate 50 is suitably fastened as by means of the screws 52, over the slide 18 and other parts previously referred to and shown in dotted lines beneath said cover plate. Adjacent one end, the slide cover plate 50 is additionally provided with a substantially half-moon shaped coin receiving opening 53 adapted to receive coins of various denominations.

In view of the foregoing description it will appear that raising the handle 10 outwardly around the pivot point 9 will cause a withdrawal of the coin follower 11 from within the opening 53 whereby a suitable coin may be inserted in the said opening 53. Subsequent movement of the handle 10 downwardly around the pivot 9 will cause the coin, which for the purposes of this illustration will be one of the size of the nickel, to move inwardly from left to right beneath the slide cover plate 50 and to thereupon engage with the cam portion 20 of the slide 18. Further movement of the handle and cam follower carried thereby will cause movement of the slide 18 toward the right, by reason of the engagement of the cam surface 16 of the cam follower 11 in engagement with the nickel, and through the nickel the cam surface 20, into a position whereby the said nickel will be permitted to slide downwardly over the corner 54 of a coin guide piece 55 now to be described. The coin guide piece 55 is of substantially rectangular conformation, provided with suitable adjusting means 56, a setscrew or the like, and includes elongated openings 57 whereby the said guide piece 55 may be adjusted to increase or decrease the distance between the rib 44 and the shoulder 54 previously referred to, the said guide piece being normally held in fixed position in its location by means of one of the screws 52 which hold the cover plate 50 in place.

It will be noted that when the slide 18 has been displaced to the right during the action above previously referred to, the cam portion 39 thereon will abut the cam section 40 of the auxiliary ball lifter lever 26 causing the same to move about the pivot 27 in a clockwise direction, the said ball lifter lever 26 engaging, in turn, the ball lifter actuator 29 by means of the portion 23, the said actuator 29 in turn rotating about the arbor 30, carrying with it the laterally projecting portion 32 which coacts with the member 36 of the ball lifter 34. Counterclockwise rotation of the end 35 of the ball lifter 34 will thereby be imparted, the said end 35 in turn abutting the ball 38 and causing the same to move upwardly along the post 37 into the position shown in Figure 2.

When the lever 10 has assumed a substantially vertical position about the pivot 9, having performed its coin moving operation and moving the slide 18 into its extreme rightward position, the shoulder 13 of the cam follower will thereupon abut the portion 23 of the ratchet dog 14 causing the same to move out of engagement with a notch 21, whereby the said slide may be permitted to move leftwardly from the said extreme right position. It will be noted that this action can only take place when the handle 10 has assumed a substantially vertical position.

In order to prevent a coin which is smaller than a nickel from being availed of to set the mechanism for a period longer than that permitted, an abutment post 58 is affixed adjacent the end of the slide 18 and of such a size that will prevent holding a coin, such as a penny, high enough in the coin receiving opening 53 whereby the same might abut the cam surface 20 of the slide 75 for a period long enough to effect any greater setting

movement than would normally be available upon the insertion of a penny.

It should be noted that the arbor 30 is provided with flat surfaces 59 formed thereon for purposes that will be hereinafter related, and is additionally provided with a round bearing surface for supporting thereon certain other of the operating parts of the device being described herein.

A consideration of Figure 4 will disclose the location of the clock mechanism generally indicated at 60 and show the arbor 30 thereof extending through the body 6, substantially centrally thereof. The clock mechanism 60 may be supported adjacent the body member 6 in any suitable manner and is provided with an indicating arm 61 fastened to the arbor by means of a suitable nut 62 thereon. This clock mechanism 60 is of any conventional form and is only generally indicated in Figure 4 since it is a well known construction.

Referring now to Figure 1, it will be seen that a timing plate 63 is supported adjacent its central portion on the arbor 30 for movement therearound, the said timing plate being formed with teeth on its periphery, said teeth being preferably cut in three degree increments in one form of the device, the said teeth being cut on a substantial portion of the periphery in a location such as will cooperate with instrumentalities to be subsequently described. The timing plate 63 is additionally provided with an abutment post 64 suitably fastened thereto. A timing plate actuator 65 (see Figure 5) is formed with an opening 66 therein for engagement and support on the arbor 30. The actuator 65 is further provided with a slot 67 adapted to receive for operation therein the post 43 of the slide 18 previously referred to for movement in a manner to be hereinafter set forth. Adjacent the outer end of the actuator 65 a pawl 68 is pivotally supported at 69 and includes a tooth engaging portion 70 formed therewith and likewise a stop shoulder 71. A suitable pawl spring 72 is fastened to the actuator 65 as by means of a rivet 73 and to the pawl by a similar rivet 74.

Outwardly of the timing plate 63 an arbor winding link 75 is rotatively supported on the arbor 30 and fixed for rotation thereof, by means of the flats 59 formed on the arbor 30, a mating opening in the winding link being adapted to receive the said flat portions. The winding link 75 is provided with a disengagement dog 76, rotatably fastened to the outer end on the pivot 77. The disengagement dog is provided with a latch section adapted to engage in a suitable opening 78 formed on the periphery of the timing plate 63, as will be clear from a consideration of Figure 1.

A spring 79 is fastened at one end to the timing plate 63 and at the other to a post 80 on the dog 76, a spring 81 in turn being fastened to the link 75 and to the post 80 on the dog 76. In view of the foregoing it will be clear that the springs maintain the latch portion of the dog 76 in engagement with the opening 78 on the periphery of the timing plate 63.

Since the post 64, carried by the timing plate 63, extends outwardly therefrom, it is adapted to be abutted by the winding link 75 during movement thereof in a manner to be subsequently set forth. It will also be clear that the pawl 68, carried by the timing plate actuator 65, is adapted to abut the arbor winding link 75 adjacent the tooth engaging portion 70 of the pawl 68, when movement in a counterclockwise direction is imparted to the timing plate actuator. It should be noted that in the position of the parts, as shown in Figure 1, the tooth engaging portion 70 of the pawl 68 is held in an inoperative position by means of a post 82 for the initial operation that will be subsequently described. In view of the foregoing it will be clear that initial rightward movement of the slide 18, which was described in relation to the description of Figure 2, will impart rotative movement to the timing plate actuator 65 since the post 43 on the said slide engages

in the slot 67 of said actuator, to effect counterclockwise rotative movement of the actuator 65. Such counterclockwise rotative movement of the actuator 65, carrying with it the pawl 68, will in turn impart similar movement to the arbor winding link 75 through abutment thereof by means of the pawl 68 previously referred to, the said winding link thereby imparting similar counterclockwise rotative movement to the timing plate 63 by reason of the abutment of said link with the post or stop 64. In view of the fact that a pointer 83 is fastened to the winding link 75 by means of a screw 84, the said pointer will likewise be carried in a counterclockwise direction. A dial plate 85 having suitable time indicia thereon, is fastened to the body member 6 by means of the screw 86 whereby the said pointer 83 will pass over the face of the dial plate 85 and indicate the timing period previously initially predetermined.

Springs 87 are provided fastened at one end to the screws 87a and around their opposite ends to the post 43 carried by the slide 18. These springs are provided to return the slide 18 from its extreme right position after the setting operation has been performed, as will be hereinafter set forth.

A consideration of Figure 1 and Figure 4 will show that the ball lifter actuator 29, timing plate 63, timing plate actuator 65, and arbor winding link 75, are supported for rotation about the arbor 30 previously referred to, and held in engagement therewith by means of any suitable nut 88 engaged in the usual manner with the outward end of the said arbor 30. In view of the fact that the arbor winding link 75 is held in fixed rotative relationship with the arbor 30 by means of flats 59 formed on the latter, adapted to be received in a co-mating opening in the said arbor winding link 75, rotation of said link will impart rotative movement through the arbor 30 to effect a winding of the spring of the clockworks 60, the usual clutch dog (not shown) being provided in the said clockworks 60 for operation in the usual manner. It will thus be seen that when initial counterclockwise rotation has been imparted to the arbor winding link the said link will remain in its set position, being held in that position by means of the dog in the clock spring mechanism. It is likewise to be understood that the arbor winding link 75 will impart similar rotative movement to the timing plate 63, by reason of the abutment of the said winding link with the stop or post 64 previously described. It should also be noted that the tension of the springs 87 in engagement at one end with the post 43 of the slide plate 18, the said post 43 being engaged in the slot 67 in the timing plate actuator 65, will normally hold the said timing plate actuator 65 in substantially the position shown in Figure 1, and thereby the pawl 68, by reason of its conformation and the abutment portion 71, will be held in engagement with the post 82 on the timing plate cover 50, whereby the said pawl 68 will remain out of engagement with the teeth of the timing plate.

When the timing plate actuator 65 has been rotated in a manner to be hereinafter described in the operation of the mechanism of the parking meter, after its initial rotation to effect a setting of the mechanism through the arbor winding link 75, subsequent rotation after return of the said actuator 65 to the position of Figure 1, will permit the tooth engaging portion 70 of the pawl 68 to engage one of the teeth on the periphery of the timing plate 63 in accordance with a predetermined setting thereof. The arbor winding link 75, after its initial winding movement, is held in an advanced rotative position such as that shown in Figure 3 so that the pawl 68 does not engage the said link 75 during its subsequent actuation.

While certain of the operating units, namely the slide and handle operating units and the arbor winding unit comprised of the timing plate actuator 65, timing plate 63 and the arbor winding link 75, have been described, a summary of the operation of these parts at this point is necessary to obtain a clear understanding of the invention

herein. While the operation of the handle and coin slide mechanism has been heretofore referred to in regard to its cooperation with a nickel or a like coin, the said operation will be described hereinafter, initially when a penny or coin of similar denomination is availed of for use therewith.

When a device of the type herein described, known as a parking meter and made in accordance with the disclosure, is supported on a post or other suitable support the handle 10 is normally in a substantially vertical position with respect to the case 2 of the said meter, as seen in Figure 1, and the same being likewise applicable to disclosure in Figure 2 which will be used initially to describe the operation as follows:

The handle 10 is grasped at the end thereof and pivoted into a substantially horizontal position whereby the coin opening 53 is uncovered and a penny is inserted in the said opening 53. Subsequent downward movement in a counterclockwise direction about the pivot 9, of the handle 10, will cause the coin follower 11 to engage the penny through the cam surface 16 of the said follower and to be carried inwardly and rightwardly (see Figure 2) whereby the said penny will engage the cam surface 19 of the slide 18 and impart a rightward displacement of the said slide. As the penny travels over the coin guide piece 55, while in engagement with the cam surface 19, and imparting bodily movement to the slide 18, the post 43 will likewise be carried to the right. Referring now to Figure 1, it will be noted that in this rightward operation or movement, the post 43 will engage in the slot 67 of the timing plate actuator 65 and impart counterclockwise rotative movement thereto. The pawl 68 carried at the end of the actuator 65 will abut the arbor winding link 75 near the pivot point 77 of the disengaging dog 76. Thus, continued movement of the post 43, as carried by the slide 18, will likewise impart the rotative movement of the actuator 65 to the arbor winding link 75. As the arbor winding link 75 is rotated in a counterclockwise direction about the arbor 30, and abuts the post 64 on the timing plate 63, it will be apparent that the said timing plate will likewise be rotated in a counterclockwise direction. When the penny has reached a point on the coin guide piece 55 (see Figure 2) denoted 54, rightward sliding movement of the slide 18 by reason of the engagement of the coin with the shoulder 19 of the said slide will have reached its maximum point. Subsequent movement of the handle 10 about the pivot 9 will cause the coin or penny to descend downwardly between the shoulder 45 and the rib 44 on the body member 6, whereby to assume a position behind the window 47 and be supported therebehind by reason of its abutment with the inwardly extending portion 49 of the coin release arm 41 which is carried by the slide 18. The rotative movement of the arbor winding link 75 has thereupon reached its maximum point, and since it carries the pointer 83, will have moved the said pointer into a position adjacent the dial plate 85, whereby the time to which the device has been adjusted will be indicated as remaining on the said dial 86. The relationship of the movements hereinbefore described, is such that the initial rotative motion imparted to the arbor winding link 75 by means of the pawl 68 carried by the actuator 65, provides a slight overrun of time, in this instance being about three minutes, for example. The initial engagement of the pawl 68 with the arbor winding link 75 is abrupt enough so that if by any chance the said pawl 68 is temporarily frozen or otherwise not freely movable upon the pivot 69 of the actuator 65, the said pawl may be broken loose, so to speak, by the impact with the said link 75, as above described.

Insertion of a second penny, moves the actuator 65 through a 15 degree arc, but the pawl 68 loses 3 degrees in entering a tooth, with a resulting net gain in time of 12 minutes.

Subsequent insertion of coins within the opening 53

in the manner above referred to will impart similar rightward movement to the slide 18, and the other mechanism associated therewith through the post 43 whereby subsequent rotative movement of the actuator 65 will cause the pawl 68 through its tooth engaging portion 70, to engage one of the teeth on the periphery of the timing plate 63, to thereby impart further rotative movement to the said plate and to the arbor winding link 75, since the said arbor link 75 is maintained in engagement with the post 64 by reason of the disengaging dog 76 employed on the said link 75, and likewise to the pointer 83 which is supported on the said link 75 for rotation therewith. It will be apparent that this rotative movement of the pointer 83 will cause the same to pass over the face of the dial plate 85 and indicate thereon the time remaining in accordance with the number of coins deposited in the manner hereinbefore set forth.

A nickel or other coin for which the device is initially arranged for use may be similarly inserted, either singly or by insertion of a plurality thereof in the same manner in which a penny is availed of for setting the mechanism.

In view of the fact that the teeth on the periphery of the timing plate 63 are spaced at 3 degree or 3 minute intervals it will be apparent that as the clock mechanism unwinds carrying with it the arbor 30 and the arbor winding link 75 and likewise the pointer 83, the insertion of a coin after a lapse of a short period of time in the opening 53 and subsequent operation in the manner hereinbefore related, will cause the tooth engaging portion 70 of the pawl 68, as carried by the actuator 65, to engage another tooth on the periphery of the timing plate 63, and impart rotative movement to the link 75 and pointer 83 in a counterclockwise direction to add the time to that already indicated on the dial plate 85. It is not necessary that the mechanism shall have moved to any particular point carrying the pointer 83 over the face of the dial plate 85 for the above action to take place. However, in certain jurisdictions the so called cumulative effect above related is not thought to be desirable and, therefore, the timing plate 63 can be provided with notches such as indicated at 89 in Figure 1, the said notches being formed so as to translate the movement of a penny only in 12 minute increments in contrast to the 3 minute increments previously described. This latter movement may be termed a noncumulative movement.

When the slide 18 has been moved to the right in response to movement of the handle 10 and a coin inserted in the opening 53, it will be apparent that, during this movement (see Figure 2) the signaling device or ball 38 will be maintained in its uppermost position on the post 37 by means of the engagement of the upper surface of the slide 18 with the camming portion 40 of the auxiliary ball lifter 26 acting on the ball lifter actuator 29 and thence on the ball lifter 34, whereby the said ball 38 is maintained in the upward signaling position throughout the rightward movement of the said slide 18. This position of the said signaling ball 38 on the upper portion of the post 37 will bring the same into a position under the plastic dome 4 whereby the same may be seen by any authorized person to indicate that a violation is taking place. When the slide 18 has been permitted to move again to its extreme leftward position (see Figure 2) by reason of the disengagement of the ratchet dog 14 with a tooth 21 on the upper surface of the said slide 18, the ball 38 will be permitted to slide downwardly on the post 37 out of position beneath the dome 4.

The parking period having been set by insertion of the coins in the manner hereinbefore described and having initiated movement of the clockworks in the usual manner, the said clock in running down will carry with it the arbor 30 moving the parts carried on the arbor, namely timing plate 63, arbor winding link 75 and pointer 83, in a clockwise direction. When the timing plate 63 has returned to the position shown in Figure 1, a stop 90 on the inner surface thereof is provided to

abut the ball lifter actuator 29 and in turn cause operation of the ball lifter 34 about the pivot 33 and raise the ball 38 into position beneath the dome 4, whereby a parking violation is indicated. It will be apparent from the foregoing that either a coin of the denomination of a penny or the like may be used in this device and similarly that a nickel or other coin of similar denomination may be used to impart a similar action to the associated parts to set the clock mechanism for various times. A safety and parking period control device is provided and will now be described whereby an overloading of the device, or an over setting of the time period may be prevented whether coins of the same or different denominations are inserted for operation in the parking meter. The disengaging dog 76 previously referred to is provided with a cam surface 91 thereon adapted to coat with a stop pin 92 located adjacent the periphery of the timing plate 63 whereby the said cam surface 91 of the dog 76 will engage the same during its maximum rotative movement as seen in Fig. 3. This engagement of the surface 91 with the pin 92 will cause the dog 76 to be rotated about the pivot 77, whereby the dog will become disengaged from the notch 78 in the periphery of the timing plate 63 and subsequent rotation of the timing plate 63 by means of the engagement of a tooth on the periphery thereof by the tooth engaging surface 70 of the pawl 68 will permit the timing plate to be rotated beyond the position shown in Figure 3 and prevent any overloading of the device. It will be apparent that location of the stop pin 92, in any one of the positions such as those indicated at 93 or 94 for example, will provide for the setting of the device for different periods of time within a wide range.

The timing plate 63 is returned to position for again engaging the dog 76, after the disengagement above described, by means of a spring 79 (see Figure 3). The spring 79 is fastened at one end to the plate 63 and the other to the dog 76 at 80. Further rotation of the plate from the position of Figure 3, in a counter-clockwise direction, will cause the spring 79 to be tensioned and act against the rotation being imparted by the pawl 68 to the plate 63. Consequently, return of the actuator 65 to initial position will permit spring 79 to contract and rotate plate 63 in a clockwise direction as will be apparent.

It should be noted that the insertion of a succession of coins will cause the coin release arm 41 to move to the right, as seen in Figure 2, and permit a previously deposited coin to drop downwardly into a suitable receptacle provided in the meter.

In view of the foregoing description of the device embodying the various novel parts and the operation of the mechanism in which they are incorporated, it will be clear that a simple parking meter has been described wherein the operation of the various parts takes place in a unique manner and coins of different sizes and denominations may be used to actuate the said meter for different periods of time. There is a positive setting of the time controlled parts for their operation throughout a predetermined period of time and the possibility of illegal manipulation of coins inserted in the device, or of the device becoming inoperative due to corrosion or freezing weather, has been eliminated. While certain of the parts are not described in detail since they may be made of various forms, a device incorporating the novel features of the one herein described is compact and readily operable to carry out the function desired.

Having thus described our invention, what we claim as new and desire to secure by Letters Patent of the United States is:

1. A parking meter of the class described, in combination, a clock mechanism having a winding arbor associated therewith, means for winding said arbor, an actuator carried by the arbor for rotative movement there-

around, a timing plate carried by said arbor for rotative movement relative thereto adapted to operate said winding means and said timing plate having a plurality of teeth formed therein, said winding means including

5 instrumentalities for disengageably connecting said means and timing plate, a slide adapted to impart rotative movement to the actuator, means for reciprocating the slide, and means carried by the actuator for engagement with the teeth of the timing plate, when the said timing plate 10 and arbor are in different rotative positions, said means carried by the actuator being adapted to initially rotate said timing plate without engaging said teeth.

2. A parking meter of the class described, in combination, comprising a timing mechanism, an arbor in the 15 said timing mechanism, an actuator pivotally mounted on the arbor, a pawl mounted on the actuator, a timing plate supported on the arbor for rotative movement relative thereto and having step means engageable by said pawl, a winding link fixed to the arbor for imparting 20 rotative movement to said arbor said link having a releasable connection with the said plate, reciprocating means for moving the actuator aforesaid, stop means on the timing plate for engagement by the winding link to effect rotation of said timing plate, said reciprocating means being adapted to impart an abrupt movement to the pawl mounted on the actuator, said pawl being mounted on the actuator so as to abut the winding link to thereby condition the pawl for subsequent rotation of the timing plate aforesaid the step means on the timing plate being engageable by the pawl to effect said 30 subsequent rotation.

3. A parking meter of the class described, in combination, comprising a clock mechanism settable for different periods of time, an arbor in the clock mechanism, a timing plate rotatably supported on said arbor, a winding link fixed to said arbor for rotation thereof including releasable normally operative means to connect said link and timing plate for rotation and release the said link and plate for separate rotation, an actuator 35 including a pawl pivotally supported on the end thereof for initial abutment with the winding link aforesaid, means for imparting rotative movement to the actuator and to the pawl carried thereby to effect winding of the clock mechanism, said pawl being subsequently engageable with said timing plate for rotation thereof.

4. A parking meter of the class described, in combination, timing mechanism, an arbor associated with the timing mechanism, a winding link fixed to the arbor for rotation thereof, a timing plate carried by the arbor including a plurality of teeth formed in said plate, means for effecting rotative movement of the winding link including an actuator carried by the arbor, means carried by the timing plate for engagement by the link to maintain the same in rotative relation therewith and release said plate and link for separate rotation to prevent overwinding of the timing mechanism, said actuator including a member adapted to engage the teeth of the timing plate aforesaid for rotation thereof when the timing plate is in different positions after initial setting of the mechanism 55 has been effected in rotative relation to the arbor previously mentioned.

5. A parking meter of the class described, in combination, a body member, timing mechanism carried by the body member, said timing mechanism including an arbor and means for setting the said mechanism into operation 65 for different periods of time, a signaling device supported on the body for movement into visible signaling and obscured nonsignaling position, a slide supported on the body member for reciprocating movement in relation thereto, means including parts cooperable with the slide and device for maintaining the signaling device in said visible signaling position during movement of the slide in one direction and means for moving the slide in said direction.

6. A parking meter of the class described, in combi-

nation, a body member, clock mechanism supported on the body member, said clock mechanism including an arbor, a timing plate supported on the arbor, a winding link engaged with the arbor for rotation of the latter said timing plate having means engageable by the link to normally compel simultaneous rotation of said plate and link, said winding link including other means for drivably connecting the winding link to the timing plate aforesaid, separate means for moving the timing plate rotatively, and stationary means carried by the body for effecting disengagement of the timing plate and winding link to permit relative rotation thereof.

7. A parking meter of the class described, in combination, a body, clock mechanism carried by the body member, including an arbor, said arbor being operable to effect winding of the clock mechanism, a timing plate on the arbor including a plurality of teeth formed in said plate, an actuator rotatably supported on the arbor, a pawl mounted on the actuator, a slide mounted on the body member for reciprocation relative thereto, means for imparting reciprocating movement to the slide, actuator engaging means fixed to the said slide for movement therewith, the pawl being supported on the actuator to impart rotative movement to the timing plate, when the said timing plate is in various different positions rotatively, and other means fixed to the arbor engageable by the pawl aforesaid, the said last named means including instrumentalities for releasably maintaining the said means in fixed rotative relation to the timing plate aforesaid, a separate member being provided to effect such release.

8. A parking meter of the class described, in combination, a body member, clock mechanism including a winding arbor, an actuator supported on the arbor for rotation relative thereto, a timing plate rotatably supported on the arbor including a plurality of teeth formed in said plate, an arbor winding link fixed to the arbor for rotation therewith, time indicating means carried by the said link, slide means associated with the body, means for operating the slide means, said slide means including an instrumentality for moving the actuator, said actuator including a member cooperable with the winding link for moving the timing plate rotatively and also adapted to engage the timing plate directly by means of the teeth formed therein, for setting the timing mechanism into operation for different periods of time, and means to return said actuator to its original position after it has performed its setting operation, said timing plate and winding link having means to compel simultaneous and facilitate independent movement thereof.

9. A parking meter as claimed in claim 8 wherein the winding link includes a disengaging member cooperable with the timing plate, the timing plate having a stop member adapted to abut the link aforesaid, and means are provided on the body member for effecting the disengagement of the disengaging member from the timing

plate whereby further rotative movement of the timing plate may be effected by the actuator without imparting additional rotative movement to the winding link aforesaid in the same direction.

10. A parking meter as claimed in claim 8 wherein a signaling device is mounted on the body member for movement into visible signaling and obscured nonsignaling positions and other means are provided for maintaining the said signaling device in visible signaling position during rotative movement of the timing plate in one direction in which winding of the clock mechanism is effected by the winding link.

11. A parking meter as claimed in claim 8 wherein the means for imparting rotative movement to the actuator include the slide the same being reciprocable with respect to the body member, a handle adjacent one end of the slide, means intermediate the handle and the slide for movement of the latter upon operation of the handle, a signaling means supported on the body member, and means cooperable with the slide aforesaid provided for maintaining the visible signaling means in signaling position during movement of the slide to effect rotation of the actuator.

12. A parking meter as claimed in claim 8 wherein stop means are provided adjacent one end of the slide means to prevent manipulation of a coin to move the slide means a different distance from that for which the parking meter is set.

13. A parking meter as claimed in claim 8 wherein the slide operating means includes a handle adjacent one end of said slide means having means cooperable with a coin for moving the slide in one direction, a dog pivotally supported on the body member and engageable with notches in the slide for maintaining the slide in various positions during its reciprocation when moved by the handle, a shoulder on the handle adapted to abut the dog for releasing the same from said notches and other means for returning the slide to its initial position with respect to the body member.

14. A parking meter as claimed in claim 8 wherein the means for operating the slide means includes a handle member and a coin follower and an adjustable coin guide piece is provided to control the length of time during which a coin remains in contact with the slide means and follower during operation of the slide means aforesaid.
